UNITED STATES PATENT OFFICE.

JOHN B. MACNEILL, OF WILKINSBURG, AND ANDREW H. BAKKEN AND CURTIS A. TUCKER, OF EDGEWOOD, PENNSYLVANIA, ASSIGNORS TO WESTINGHOUSE ELECTRIC AND MANUFACTURING COMPANY, A CORPORATION OF PENNSYLVANIA.

SWITCH MECHANISM.

Application filed November 2, 1921. Serial No. 512,194.

Our invention relates to switch mechanism and particularly to switch mechanism for interrupting high-power circuits and which includes a disconnecting switch and an oil 5 switch or circuit breaker.

One object of our invention is to provide a combined disconnecting switch and circuit breaker which constitutes a complete unit, such as is particularly adapted for use on 10 boats or in other locations where space economy is essential or desirable.

Another object of our invention is to provide a switch mechanism, of the above-indicated character, that may be conveniently 15 mounted in a structural frame in such manner that a plurality of similar switch devices may be located side by side and in superimposed relation in order to constitute a compact bank of switches, all of which are readily 20 accessible for inspection and repair.

Another object of our invention is to provide switch mechanism with a simple and effective operating mechanism of such character that two or more switch devices may 25 be conveniently connected for simultaneous operation and wherein the operating mechanism of co-operating switch devices may be disconnected when desired, but only when the switches are open.

Another object of our invention is to provide switch mechanism having the above characteristics wherein the disconnecting switch and the circuit breaker are so interlocked that the former cannot be opened so 30 long as the latter is in closed position.

Another object of our invention is to provide a combined disconnecting switch and circuit breaker wherein the circuit breaker cannot be closed so long as the disconnecting 35 switch is open.

Another object of our invention is to provide a combined disconnecting switch and circuit breaker wherein the circuit breaker is movable bodily into and out of engagement 40 with the disconnecting switch and wherein bodily movement of the circuit breaker is precluded so long as the circuit breaker is closed.

Another object of our invention is to provide 45 a convenient disconnecting switch and oil circuit breaker wherein the oil tank for enclosing the circuit breaker cannot be removed so long as the circuit breaker is in closed

position, and wherein the circuit breaker cannot be closed while the tank is in such position that it may be either removed or replaced.

A further object of our invention is to provide a combined disconnecting switch and circuit breaker wherein the circuit breaker is opened with a quick action.

These and other objects that will be made apparent throughout the further description of the invention are attained by means of the switch mechanism hereinafter described, and 65 illustrated in the accompanying drawings, wherein:

Figure 1 is a view of our switch mechanism, partially in section and partially in elevation;

Fig. 2 is a front elevational view of the mechanism shown in Fig. 1;

Fig. 3 is a view of a fragment of the device shown in Fig. 1, partially in section and partially in elevation, and showing details 75 of the interlocking mechanism, and

Fig. 4 is a front elevational view showing a portion of the switch mechanism.

Referring to the drawings, the apparatus includes a structural frame which consists of 80 a plurality of upright members 4 formed of commercial angle iron. The upright members are connected by means of a cast-metal support 5 which is secured thereto by means of bolt 6. The support 5 serves to rigidly 85 connect the upright members and to support the stationary contact members 7 of the disconnecting switch 8.

The switch mechanism herein illustrated is of the three-pole type and, therefore, six of 90 the stationary disconnecting-switch contact members 7 are required. The contact members 7 are secured to terminal members 9 which extend through insulating bushings 11 and by means of which they are secured to 95 the support 5 by bolts 12.

The upright members 4 at the front of the switch mechanism are connected by means of a metal bracket 13 which serves to support the lower ends of guide bars 14 which extend 100 between the bracket 13 and the support 5 and are secured thereto at their upper ends. The guide bars 14 provide a guide for a supporting frame 15 upon which the circuit breaker is mounted. The support 15 is provided with two sleeve-like structures 16 which

are slidably mounted on the guide bars 14 and permit vertical movement of the supporting frame with respect to the support 5.

The disconnecting switch comprises three pairs of contact members 20 that are adapted to move with the frame 15 and engage corresponding contact members 7 of the disconnecting switch 8. Each contact member 20 comprises a conductor bar 17 which extends through insulating bushings 18 and 19 that are disposed on opposite sides of the frame 15. The upper end of the bar 17 is provided with a contact member 21 having tapered blade-like members 22 which register with the yielding switch jaw members 23 of the contact members 7 of the disconnecting switch. The lower end of the conductor bar 17 is provided with a pair of switch-jaw members 24 that are somewhat similar to the contact-jaw members 23 on the contact members 7. The insulating bushings 19 are secured to the frame 15 by means of bolts 25 and serve to support the contact bar on the frame and insulate it therefrom.

As illustrated in the drawings, it will be seen that the contact members 7 and the contact members 20 are arranged in three pairs upon the supporting structure and it will be understood that the current through each phase of the switch passes through one of the terminals 9, downwardly through the conducting bar 17, across the oil-switch member to be hereinafter described, and upwardly through the conducting bar 17 of the other contact member of the pair and finally through the other terminal member 9.

Each oil switch for connecting the contact-jaw members 24 of each pair of contact members consists of a bar 26 upon the ends of which are carried tapered wedge-like contact members 27 that are adapted to conductively engage the contact-jaw members 24 when moved upwardly with respect thereto. The bars 26 of each switch are supported upon downwardly projecting rods 28 that are suspended from a movable supporting member 29 which, as shown in Figs. 1 and 2, is mounted between the contact members 20 of the different sets thereof. The support 29 is suspended by means of a link 31 from the rocking link 32 that is pivoted, at its front end, to the supporting frame 15 by means of a pin 33.

The link 32 is supported in its elevated or closed position, indicated in Fig. 1, by means of a link 34 that is pivoted, at one end, to the central portion of the link 32 by means of a shaft 35 and, at its lower end, to an operating lever 36 by means of a pin 37. The lever 36 is pivoted to the support 15 by means of a pin 38, and the short end 39 of the lever 36, together with the link 34, constitutes a toggle which serves to hold the link 32 and the switch mechanism in closed position when the toggle links are in the "made" position indicated

in Fig. 1, wherein it will be seen that the shaft or knee pivot 37 of the toggle occupies a position slightly above a line traversing the axes of the pins 38 and 35. When the toggle is in the "made" position, the long end of the lever 36 engages the support 15 at the point 41 which prevents further counter-clockwise movement of the lever and holds the toggle in the "made" position.

The oil switch or circuit breaker is operated by means of an operating rod 42 which is provided, at its upper end, with a slot 43 in which the pin 44 of the lever 36 operates. The rod 42 is provided, at its lower end, with a slot 45 through which a pin 46 projects and which serves as a guide for the lower end of the rod 42. The rod 42 may be connected to an operating rod 47 which serves to operate a similar oil switch arranged in a tier directly beneath the switch herein illustrated or may be attached to any preferred operating means, as desired.

In order to open the circuit breaker by moving the contact members 27 downwardly out of engagement with the contact-jaw members 24, the operating rod 42 is moved upwardly until the lower end of the slot 43 engages the pin 44 of the lever 36. The upper end of the slot 43 will then be raised above the pin 44 and will permit of movement thereof when the lever 36 has finally been moved upwardly until the pin 37 of the toggle knee has been moved downwardly past the "dead center" of the toggle. When this has occurred, the toggle will collapse into broken position and permit the switch-contact members 27 to fall away from the contact-jaw members 24 with a quick action by reason of the force of gravity. Downward movement of the operating rod 42 will cause the switch members to be raised into engagement with the contact-jaw members 24 and close the circuit breaker.

As shown in the drawings, the contact members 22 are in engagement with the contact-jaw members 23 of the disconnecting switch 8. When it is desired to open the disconnecting switch, the frame 15 is lowered to move the circuit breaker bodily away therefrom. The circuit breaker is bodily moved by means of an operating lever 48 that is pivoted to the frame 13 for rotation about the shaft or pin 49. The lever 48 is connected to the supporting frame 15 by means of a link 51 that is pivoted, at its lower end, to the lever 48 by means of a pin 52 and, at its upper end, to the frame 15 by means of a shaft or pin 53.

As shown in full lines, the disconnecting switch is in closed position and the operating handle 48 is in its lowermost position. When the operating lever is moved to the position indicated by broken lines in Fig. 1, the link 51 is drawn downwardly to the position indicated by broken lines and the pivot shaft 53 is moved to the position indicated by

dotted lines. The entire circuit breaker is moved downwardly and the contact members 22 thereof are moved out of engagement from the contact-jaw members 23 of the disconnecting switch. When the operating lever 48 is returned to its original position, the frame 51 is moved upwardly, carrying with it the contact members 22 which are moved into engagement with the contact-jaw members 23.

10 It will be observed, by reference to Figs. 1 and 3, that, when the operating lever 48 is moved to closed position, shown by full lines, the pin 52 lies to the front or left of a line traversing the shafts 49 and 53 of the operating lever 48 and the support 15, respectively, and that the switch is retained in the closed position indicated by reason of the "made" position of the toggle constituted by the link 51 and the lever 48. Therefore, the circuit breaker is automatically retained in closed position.

15 A tank 54 is secured to the underside of the frame 15 by means of suspension rods 55 which are secured to the frame 15 at their upper ends and project downwardly beyond the bottom of the tank 54 at opposite sides thereof. The lower ends of the rods 55 are threaded and the tank is supported upon bars 56 having perforations through which the rods 30 extend. The bars 56 are retained upon the rods 55 by means of wing nuts 57, and the tank 54 is supported upon the bars 56. It will be seen from the foregoing that, when the wing nuts are removed, the bars 56 may be 35 removed and the oil tank 54 detached from the support 15 for the purpose of filling or for the inspection and repair of the circuit-breaker parts.

20 It is an object of our invention to prevent opening movement of the disconnecting switch while the circuit breaker is closed and to prevent the closing of the circuit breaker while the disconnecting switch is open. Means are, therefore, provided to insure the proper sequence of operation of the disconnecting switch and the circuit breaker and means are also provided to prevent the removal of the oil tank so long as the circuit breaker is in closed position, or so long as the disconnecting switch is in closed position.

25 Referring to the drawings, and particularly to Figs. 1 and 3, it will be seen that the operating rod 42 is provided with a lug 58 having arcuate ends. The operating lever 48 is provided with an arcuate recess 59 having a curvature corresponding with the curvature of the ends of the lug 58. When the disconnecting switch and the circuit breaker are in the closed positions illustrated in Fig. 30 1, the upper portion of the lug 58 is disposed across the path of movement of the lug 61 secured to the operating lever 48. By reason of the position of the lug 58, clockwise rotation of the lever 48 is prevented and, consequently, the circuit breaker cannot be lowered

away from the disconnecting switch so long as the operating rod 42 and the contact members 27 of the circuit breaker are in closed position. When the circuit breaker has been moved to open position by upward movement 70 of the rod 42 to its extreme upper position, the lug 58 is moved to the position indicated in broken lines in Fig. 1 and out of the path of movement of the lug 61 of the operating lever 48, which may then be rotated clockwise, without interference, to the open position indicated by dotted lines in Fig. 1, thereby causing the circuit breaker and the contact members 22 to be moved out of engagement with the contact-jaw members 23. 75 When the lever 48 is in its open position, indicated in dotted lines in Fig. 1, the arcuate recessed portion 59 of the lever prevent either upward or downward movement of the operating lever 42 because the curved portions 80 thereof extend over the ends of the lug 58, carried on the rod 42. It will be seen, therefore, that, so long as the contact members 22 are out of engagement with the contact-jaw members 23 of the disconnecting switch, closing movement of the circuit breaker is prevented. 85

90 The operating lever 48 is provided with an arm 62 which projects rearwardly in such manner that the end thereof is disposed beneath the tank 54 when the disconnecting switch is closed or when the circuit breaker and tank are in raised position. It is, therefore, impossible to remove the tank so long as the arm 62 remains in a position beneath the tank, and the tank can, therefore, only be removed after the operating lever 48 has moved to open position wherein the disconnecting-switch elements are in open position. 95

100 In order to insure that the operating rod 42 may not be disconnected from the connecting rod 47 while the circuit breaker is in closed position, a guard plate 63 is secured to the bracket 13 and is provided with a circular opening 64 with which a connecting pin 65, which serves to connect the rod 42 with the connecting rod 47, registers only when the rod 42 is in its open position. The pin 65 may then be withdrawn from the connecting rod 47 through the perforation 64. 105

110 It will be seen from the foregoing that each switch unit is practically self-contained and of a very compact nature and that a plurality of switch devices having the characteristics of the devices above described may be arranged side by side and in superimposed relation. In this event, the structural framework is extended to provide as many supports for the switch devices as may be required. The construction is rugged and compact and is designed so that the parts thereof are readily accessible from the front and the rear of the supporting structure. 115

120 While we have described and illustrated but one embodiment of our invention, it will 125

be apparent to those skilled in the art that various changes, modifications, substitutions, additions and omissions may be made in the apparatus illustrated without departing 5 from the spirit and scope of the invention, as set forth in the appended claims.

We claim as our invention:

1. Switch mechanism comprising a switch member movable to open and closed positions, means for operating the said switch member, a connector therefor, a pin for detachably connecting the operating means with the connector, and a perforate plate for preventing disconnection of the said pin so long 10 as the switch member is in closed position.

2. Switch mechanism comprising a switch member movable to open and to closed position, detachable means for operating the said switch member comprising an operating 20 rod and a pin, and a perforate plate for preventing removal of the pin so long as the switch is in closed position.

3. Switch mechanism comprising a disconnecting switch contact member, a circuit 25 breaker movable bodily into and out of engagement with the said contact member, means for bodily moving the circuit breaker,

a tank enclosing the circuit breaker and supported thereon and detachable therefrom and means carried by the said moving means for preventing disconnection of the tank from the circuit breaker while the said breaker is in engagement with the said contact member.

4. Switch mechanism comprising a disconnecting switch contact member, a circuit breaker movable bodily into and out of engagement with the said contact member, a tank enclosing the circuit breaker and supported thereon and detachable therefrom, 30 means for moving the circuit breaker into and out of engagement with the said contact member and means associated with the said means for preventing disconnection of the tank from the said circuit breaker while the 35 breaker is in engagement with the said contact member.

In testimony whereof, we have hereunto subscribed our names this 24th day of October, 1921.

JOHN B. MACNEILL.
ANDREW H. BAKKEN.
CURTIS A. TUCKER.
